COSMETIC APPLICATOR

Chester H. Braselton, New York, N. Y.

Application January 9, 1948, Serial No. 1,355

7 Claims. (Cl. 206—56)

1

This invention relates to certain improvements in cosmetic applicators such as lipsticks, and aims generally to improve the construction and operation of lipsticks in general as well as those shown in the disclosures made in my following co-pending applications: Serial No. 699,025, filed September 24, 1946, entitled "Lipstick" (patented December 28, 1948, Patent No. 2,457,342); Serial No. 699,026, filed September 24, 1946, entitled "Retractable Lipstick," patented August 21, 1951, Patent No. 2,565,346; Serial No. 751,035, filed May 28, 1947, entitled "Non-Retractable Lipstick"; Serial No. 755,607, filed June 19, 1947, entitled "Manual Feeding Lipstick"; Serial No. 756,598, filed June 24, 1947, entitled "Manual Feeding Retractable Lipstick"; and Serial No. 782,536, filed October 28, 1947, entitled "Lipstick," patented March 20, 1951, Patent No. 2,455,444.

It is the present custom in the manufacture of lipsticks to provide a lipstick container within which is situated a bar or solid cylinder of lipstick material which may be applied to the lips when the protective cap for the casing is removed. I have shown in my previously cited applications numerous improvements in the general construction of this type of lipstick and have disclosed a detachable type of cartridge with a unique lipstick applicatory surface, which may be used in conjunction with some lipstick casings now used, to provide protection for the lipstick material, as well as greater ease and accuracy in the proper application of the lipstick material to the lips. In this particular type of cartridge I have also provided means for feeding the lipstick material within the cartridge toward the applicatory surface of the working end as the lipstick material is consumed. As I have pointed out, such a cartridge may be detachable from the lipstick casing and therefore a particular shade of lipstick may be quite easily replaced by another cartridge containing a different shade. Such replacement procedure does, however, constitute a certain amount of inconvenience, especially so in view of the present day trend toward using different shades of lipstick for different lighting conditions throughout the day and evening.

It is a purpose of this invention to provide a general construction for a lipstick which will make available two shades of lipstick housed in the same common carrier with each shade of lipstick matter being protected by a separate cover, and which may be made serviceable by removal of the appropriate cap.

2

It is another object of this invention to describe a method of mechanical construction pertaining to a lipstick holder arranged to dispense two shades of lipstick material from the opposite ends of a tube-like holder, the lipstick matter of each particular shade in turn being housed by a lipstick cartridge which is adapted for detachability from the dual carrier housing, and which while in place in said carrier rests in driving relationship with respect to the same, allowing feeding of the lipstick material within the cartridge by relative rotation of a portion of the cartridge with respect to the casing.

It is further an object of this invention to disclose a means of frictionally retaining a lipstick protective cap on a lipstick housing which is simple and economical of construction and obviates the possible viewing of worn surfaces attendant with such frictional retaining methods, said means being particularly useful in connection with the protective caps for foregoing dual lipstick holder casing and the cartridge type lipsticks of this and my other applications.

It is further an object of this invention to describe a method for economically achieving the aforesaid purposes by a construction utilizing in a number of its features sections of standard size tubing.

In the drawings,

Fig. 1 is an elevational view of an embodiment of my invention providing mounting for two shades of lipstick in cartridge form with the protective caps for the lipstick elements shown in place;

Fig. 2 is a longitudinal sectional view of the dual lipstick shown in Fig. 1, with the protective caps in place, the caps being shown in dotted lines;

Fig. 3 is a longitudinal sectional side view of my dual lipstick shown in Fig. 2, taken on the line A—A of Fig. 2, looking in the direction of the arrows, but with the protective caps removed;

Fig. 4 is a longitudinal sectional view, to an enlarged scale, of the central portion of my lipstick as illustrated in Fig. 2;

Fig. 5 is a longitudinal sectional view, to an enlarged scale, of the central portion of my lipstick, as illustrated in Fig. 3, taken at right angles to the view of Fig. 4;

Fig. 6 is a cross-sectional view of the open end of a lipstick cap embodying my invention;

Fig. 7 is a cross-sectional view of the open end of a modified form of cap embodying my invention;

Fig. 8 is a cross-sectional view of the open end of another modification of cap embodying my invention;

Fig. 9 is an elevational view of a single cartridge lipstick with my improved method of mounting the lipstick protective cap;

Fig. 10 is a longitudinal sectional view of the lipstick shown in Fig. 9, showing in more detail the arrangement providing mounting for the lipstick cap;

Fig. 11 is a longitudinal sectional view of the embodiment shown in Fig. 10, taken on the line A—A of Fig. 10, looking in the direction of the arrows thereon;

Fig. 12 is a longitudinal sectional view, to a larger scale, of the lower portion of the lipstick shown in Fig. 10; and

Fig. 13 is a longitudinal sectional view of the lower portion of the lipstick as shown in Fig. 11, taken at right angles to the view shown in Fig. 12.

The lipstick shown in Fig. 1 is a preferred embodiment of my invention relating to the mounting of two lipstick cartridges having different shades of lipstick in a common casing. The protective caps 1 and 2 are shown in place on the casing 3. As better shown in Figs. 2 and 3—Fig. 3 being a longitudinal sectional view of Fig. 2, taken on the line A—A of Fig. 2, and looking in the direction of the arrows thereof—my dual lipstick provides detachable mountings for two lipstick cartridges 4 and 4a adapted to contain lipstick material 5 and 5a. The particular form of cartridge shown is preferably of the type described in my previously cited applications wherein the cartridge 4 and 4a have working ends 6 and 6a, respectively, which flat-frame and define an improved applicatory surface for the lipstick material. Since the two lipstick cartridges 4 and 4a are identical in mechanical construction and the lipstick casing or holder providing mountings for these two lipstick cartridges is symmetrical about the center line B—B in Figs. 2, 3, 4 and 5, for clarity and ease of description I shall describe only the relationship of the cartridge elements to the left of the center line B—B in the illustrations of this embodiment. As the lipstick material 5 is consumed at the working applicatory surface 6 of the cartridge 4, the piston 7, which is threadedly engaged on feed screw 8 may be advanced toward the working end 6 by relative rotation of the rotatable closure 9 and the cartridge wall 4. The rotatable closure 9 is disposed to rotate freely in the counterbored and spun-over interior section 10 of the cartridge wall 4, and to this rotatable closure 9 is rigidly fastened the feed screw 8. A longitudinal spline 11, mounted on the inner wall of the cartridge 4, cooperates with a notch 12 in the periphery of the piston 7 so as to restrain the piston 7 from rotation with respect to the cartridge wall 4, but permit its axial movement as in feeding the lipstick material 5 toward the working end 6 of the cartridge as it is driven by the feed screw 8.

The rotatable closure 9 from its bored out and transversely slotted annular extension 13 having a U-shaped clamping spring 14 fixed therein, is adapted to drivingly engage transverse driving pin 15 loosely mounted in diametrically opposite holes in the wall of the casing 16. This is most clearly seen in Figs. 4 and 5, which are representations of the central portion of Figs. 2 and 3 respectively, but drawn to a larger scale. This particular method of cartridge closure driving

engagement with the transverse pin 15 is described more exhaustively in my previously cited application, Serial No. 782,536, filed October 28, 1947, entitled "Lipstick," wherein the advantages 5 of mounting spring clamp 14 on the closure 9 in axial alignment with the slot 17 in the periphery of the annular extension 13 of the closure 9 is more fully disclosed. However, when the lipstick cartridge 4 is in place in the casing 16 the 10 diametrically disposed transverse slot 17, in the annular extension 13 of the cartridge closure 9, surrounds the transverse driving rod 15 while the restriction of the U-shaped spring clamp 14, mounted in alignment with that slot, provides 15 snap-acting engagement of the rod by the spring clamp and holds the cartridge 4 in driving relationship with respect to the driving rod. As it is shown, the driving rod 15 is mounted in large clearance holes 18 and 19 in the walls of the 20 casing 16. These enlarged holes provide sufficient movement of the driving rod 15 in its mounted position to considerably increase the permissible tolerances in the overall construction of the lipstick and still allow reliable engagement of the pin by the cartridge slot 17 and spring clamp 14. It is therefore seen that in the 25 mounted position of the cartridge 4 within the casing 16, shown in Figs. 2, 3, 4 and 5, the rotation of the cartridge 4 with respect to the casing 16 through the driving action of the slot 17 and the 30 driving pin 15 will cause rotation of the feed screw 8 with respect to the cartridge wall 4, and hence effect axial movement of the piston 7 within the cartridge, causing feeding of the lipstick 35 material toward the working end 6 of the lipstick cartridge.

The holes 18 and 19 for mounting the driving pin 15 are shown to extend through the walls of the casing 16. Hence the cap hub 20 on which 40 the protective cap 1 is held is made to cover these mounting holes. The cap hub 20 is held in place by solder or other suitable adhesive 21, common to the casing 16 and the cap hub 20. A decorative ring 3 is in turn fastened to the outer periphery of the cap hub 20 by other suitable adhesive 22. This protective ring 3, as best shown in Fig. 5, tends to hide from view the wearing of surface 20' or 20a' of the cap hub 20 when the protective caps are not in place.

50 As previously stated the dual lipstick casing as shown in Figs. 2, 3, 4 and 5 is symmetrical about the center line B—B, hence, all that has been said about the relation of elements of the left of said line B—B may also be said relative to the 55 identical elements to the right of center line B—B, which are designated by the suffix "a." For example the cartridge 4a to the right of the center line in Fig. 2 with its driving rotatable closure 9a and driving pin 15a is identically equivalent 60 to the elements, 4, 9 and 15 to the left of the center line B—B.

In order that the protective caps 1 and 2 may be held by the circular cap hub 20 the protective caps 1 and 2 may be distorted in circularity as 65 shown in modified forms in Figs. 6, 7 and 8. In Fig. 6 the open or mounting end of the cap 23, shown in cross-section therein, has been distorted so that the opposite inner surfaces 23a and 23b are closer to the axis of the cap than the remote 70 inner surfaces 23c and 23d. The distortion of the mounting end of the cap 23' shown in Fig. 7 results in inner surfaces 23a', 23b' and 23c' being distorted in toward the axis of the cap preferably equidistant therefrom. In Fig. 8 distortion has 75 been slightly modified to provide four inner sur-

faces of bearing for the lipstick cap wherein surfaces 23a'', 23b'', 23c'' and 23d'' are distorted toward the axis of the tube preferably equidistant therefrom. However, whichever distortion is used it is clear that when such distorted cap is placed on the circular cap hub 20 of my dual lipstick there must necessarily be a springing or yielding of the cap material to conform to the circularity of the cap hub 20. This yielding of the protective cap material provides a frictional spring action between the cap hub 20 and the inner surface of the protective cap sufficient to detachably hold the protective cap in place on the lipstick casing. As best shown in Fig. 3, the clearance 24 between the decorative ring 3 and the cap hub 20 is sufficient to prevent the contact of decorative sheath 3 with the outer surface of the protective cap 1 or 2. This particular feature is desirable in that it eliminates any evidence of wearing on the outside of the protective caps.

It is therefore seen that I have provided a detachable mounting for two cartridges, which may contain different shades of lipstick material, within a common lipstick casing, said mounting providing driving action between the casing and the feeding mechanisms within the lipstick cartridges. I have further provided a simple and effective manner of mounting and holding the protective caps for said cartridges on the lipstick casing which is artistic in appearance and prevents viewing of worn surfaces of the lipstick casing or the protective cap when the protective cap is removed.

It is clearly evident that my improved method for mounting the lipstick protective cap on the casing may be applied to a single-element lipstick which may be of the general form shown in Figs. 9 to 13. As better shown in Figs. 10, 11, 12 and 13 the method employed to hold the protective cap 25 on the casing wall 27 is by means of cap hub 28 similar to the arrangement in my dual lipstick hereinbefore described. The cap hub 28 has a protective ring 26 which surrounds and is fastened to the outer surface of cap hub 28 by solder or other suitable means. As best shown in Fig. 12, the preferred method for assembling such a construction is to first insert the driving rod 30 in the holes 31 and 32 of the casing wall 27. This driving rod 30 cooperates with the closure 33 of the lipstick cartridge 34 by means of slot 35 and spring 36 mounted on said closure to provide driving activation of the feeding mechanism 37 within the lipstick cartridge 34 whenever the sleeve of the lipstick cartridge 34 is rotated relative to the casing 27, as in embodiments heretofore described. After the driving pin 30 is mounted in the holes 31 and 32 of the casing wall 27 the cap hub 28 is then put in place to cover the mounting holes for the driving pin 30 and retain the pin therein, as well as to provide support for the protective cap 25, the cap hubs being fastened to the housing wall 27 by solder or other suitable adhesive 38. The circular end closure 39 for the lipstick casing end is then put in place and fastened to the exposed end surface of the casing wall 27 and the cap hub 28 by solder or other suitable adhesive 40. Finally the protective ring 26 is placed to surround the lower end of the lipstick casing as shown in Figs. 12 and 13, and is in turn brazed, soldered or otherwise fastened at 41 to the peripheral surface of the cap hub 28 in combination with the casing end closure 39. The cap 25 is distorted in a non-circular manner, such as in Figs. 6, 7 or 8, above,

so as to present frictional resistance in its placement on the cap hub 28, which frictional resistance serves to maintain the cap 25 in position on the casing.

5 Although I have described my invention in particular detail and applied it to preferred embodiments as shown herein, I contemplate many useful variations of the constructions shown as may be applied to other forms and combinations without, however, departing from the spirit of my invention as defined in the following claims.

What I claim is:

1. In a lipstick or the like, a common base member having tubular openings at both its ends, cosmetic paste cartridges adapted to enter said openings, said paste cartridges having rotatable sleeve-like bodies to protrude from said openings and paste-feeding elements therein, and separable-retaining and feed-driving means carried in part by said cartridges and in part by said base and engaging when said cartridges are pushed into said base to retain said cartridges therein and establish a driving connection between said paste-feeding elements and said base.

25 2. In a lipstick or the like, a common base member having tubular openings at both its ends, cosmetic paste cartridges comprising rotatable sleeve-like bodies having applicatory surfaces at one end and having their other ends adapted to enter said openings, said cartridges having therein paste-feeding elements for advancing cosmetic paste toward the applicatory ends of the cartridges, and push-in assembling and feed-driving means carried in part by said cartridges and in

30 35 part by said base and engaging when said cartridges are pushed into said base to retain said cartridges therein and establish a driving connection between said paste-feeding elements and said base whereby a dual applicator is afforded 40 having applicatory surfaces at both its ends and capable of continuously presenting cosmetic paste in usable position at both of said applicatory surfaces.

3. In a lipstick or the like, a common base member having tubular openings at both its ends, cosmetic paste cartridges adapted to enter said openings, said paste cartridges having rotatable sleeve-like bodies to protrude from said openings and paste-feeding elements therein, push-in assembling and feed-driving means carried in part by said cartridges and in part by said base and engaging when said cartridges are pushed into said base to retain said cartridges therein and establish a driving connection between said paste-feeding elements and said base, hubs on the outside of said casing base presenting externally facing friction surfaces, sleeve-like protective caps formed to pass over said cartridges and internally engage said externally facing friction surfaces and be frictionally retained thereby in cartridge housing position, and a decorative and protective ring surrounding said hubs and lying in spaced relation to said protective caps when the latter are in place on the casing, and concealing said friction surfaces when said caps are removed therefrom.

4. In a lipstick or the like, a common base member having tubular openings at both its ends, cosmetic paste cartridges comprising rotatable sleeve-like bodies having applicatory surfaces at one end and having their other ends adapted to enter said openings, said cartridges having therein paste-feeding elements for advancing cosmetic paste toward the applicatory ends of the cartridges, and push-in assembling and feed-driving

means carried in part by said cartridges and in part by said base and engaging when said cartridges are pushed into said base to retain said cartridges therein and establish a driving connection between said paste-feeding elements and said base, hubs on the outside of said casing base presenting externally facing friction surfaces, sleeve-like protective caps formed to pass over said cartridges and internally engage said externally facing friction surfaces and be frictionally retained thereby in cartridge housing position, and a decorative and protective ring surrounding said hubs and lying in spaced relation to said protective caps when the latter are in place on the casing, and concealing said friction surfaces when said caps are removed therefrom.

5. In a lipstick or the like, a base member having a tubular opening at one end, a cosmetic paste cartridge adapted to enter said opening, said paste cartridge having a rotatable sleeve-like body to protrude from said opening and paste-feeding means therein, push-in assembling and feed-driving means carried in part by said cartridge and in part by said base and engaging when said cartridge is pushed into said base to retain said cartridge therein and establish a driving connection between said paste-feeding elements and said base, a hub on the outside of said casing base presenting an externally facing friction surface, a sleeve-like protective cap formed to pass over said cartridge and internally engage said externally facing friction surface and be frictionally retained thereby in cartridge housing position, and an external ring on said base surrounding said friction surface and lying in spaced relation to said protective cap when the latter is in place on the casing, and concealing said friction surface when said cap is removed therefrom.

6. In a lipstick or the like, a base member having a tubular opening at one end and having a hub member facing said end and presenting an externally facing cylindrical friction surface, a lipstick cartridge mounted in said opening and projecting therefrom, a cartridge enclosing protective cap extending about said cartridge and internally engaging said externally facing fric-

tion surface and frictionally but removably retained thereby in cartridge housing position, and an external ring on said base surrounding said friction surface said ring being internally cylindrical and of a length at least equal to that of the external friction surface and lying in spaced relation to said protective cap when the latter is in place on the base and concealing said external friction surface when said cap is removed from the base.

7. In a lipstick or the like, a base member having a tubular opening at one end and having a hub member facing said end and presenting a cylindrical friction surface, a lipstick cartridge mounted in said opening and projecting therefrom, a cartridge enclosing protective cap member extending about said cartridge and presenting a cooperating friction surface engaging the friction surface of said hub on one face only and frictionally but removably retained thereby, one of said friction surfaces being an external surface and the other an internal surface, and the member having the external friction surface being further provided with an external ring surrounding said external friction surface, said ring being internally cylindrical and of a length at least equal to that of the external friction surface and lying in overlapping but non-contacting relation to the adjacent surface of the other member when the cap is in place and concealing said external friction surface when the cap is removed.
